John, Harris, Gamelle,
Hubbays.

UNITED STATES PATENT OFFICE.

GEORGE H. LOGAN, OF PITTSBURGH, PENNSYLVANIA, ASSIGNOR OF ONE-FOURTH TO EDWARD A. HORIGAN AND ONE-FOURTH TO EDWARD L. HORIGAN, BOTH OF PITTSBURGH, PENNSYLVANIA.

DRUM.

Application filed December 26, 1922. Serial No. 609,154.

The present invention relates broadly to drums, and more particularly to an improved shell construction thereof and improved means for tightening the heads.

It has heretofore been proposed to construct drums of this general type with a shell comprising a series of independent members secured or held in assembled relationship by suitable fastening means; such construction having been found objectionable to a certain extent, however, because of the relative vibratory movements between the different members, thereby producing discord. By the present invention, there is provided an improved shell, preferably comprising a single casting by means of which the tones of the drum are greatly improved.

This invention also has for an object the provision of improved means for tightening the heads, whereby all of the tightening members are maintained in axial alignment.

In the accompanying drawings there are shown for purposes of illustration only certain embodiments of this invention, it being understood that the drawings do not define the limits of the invention as changes may be made in the construction without departing from the spirit and scope of my broader claims.

In the drawings:

Figure 1 is a perspective view of a drum constructed in accordance with the present invention;

Figure 2 is a sectional view on an enlarged scale through the shell; and

Figure 3 is a view corresponding generally to Figure 2, but illustrating a modified form of construction.

In carrying out the present invention, there is provided a shell 2, preferably in the form of a single casting of aluminum having integral reinforcing bands 3. As is customary in this art, these bands are preferably located adjacent the edges and the central portion of the shell.

The heads 4 may be secured to the drum in the usual manner by securing the edges to hoops 5 and fastening the hoops over the ends of the shell 2. Rings 6 are then placed in engagement with the hoops and tightening screws 7 are inserted through the openings in the lugs 8 on the rings.

It is desirable in order to prevent any torsion or binding of the tightening screws

7 to provide a construction wherein they are maintained in true axial alignment during the tightening of the heads and the use of the drum. This is accomplished in accordance with the present invention by the use of sleeves 9, adapted to receive the tightening screws.

In the form of the invention illustrated in Figure 2, the sleeves 9 are adjustably carried on the threaded outer extremity of posts 10, which posts are rigidly secured to and project outwardly from the shell. By threading the sleeves inwardly or outwardly on the post 10, it is possible to so position the same that the tightening screws 7 may enter the sleeves without any binding action. The tightening screws may then be drawn up in the usual manner.

In Figure 3, there is illustrated a slightly modified embodiment of the invention, in which the sleeves 9' are formed integrally with the posts 10'. The posts, in turn, have projecting inwardly therefrom threaded extensions 11, which are threaded in suitable openings in the central reinforcing band 3.

With both of the forms of the invention illustrated, it will be apparent that means are provided for producing relative adjustment between the shell and the sleeves and for holding the sleeves in adjusted positions. It has been found that it is impossible to obtain these results by utilizing a construction in which a free sliding movement is permitted between the sleeves and the posts.

It will be apparent that, due to the one-piece construction of the shell, the resonant qualities thereof are greatly improved, thereby insuring better results. Other advantages arise from the improved form of tightening means, in which the rings are always drawn in a true axial direction and the tightening screws are maintained in axial alignment.

I claim:

1. In a drum, a shell comprising a casting having integral reinforcing bands adjacent its upper and lower edges, substantially as described.

2. In a drum, an aluminum shell comprising a casting having integral reinforcing bands adjacent its upper and lower edges and its center, substantially as described.

3. In a drum, a shell, a plurality of posts projecting outwardly therefrom, tightening

100

105

110

sleeves carried by each of said posts, and means for producing positive adjustment between the shell and sleeves and for holding the sleeves in adjusted positions, substantially as described.

4. In a drum, a shell, a plurality of posts projecting outwardly from said shell, sleeves carried by said posts, a threaded adjustment intermediate said sleeves and said shell for adjusting the sleeves inwardly or outwardly with respect to the shell, and tightening screws cooperating with said sleeves, substantially as described.

5. In a drum, a one-piece shell having an integral central reinforcing band, and integral reinforcing bands adjacent its upper and lower edges, a plurality of posts projecting outwardly through said shell and having fastening means cooperating with said central band, sleeves carried by said

posts and adjustable with respect to said shell, and tightening screws cooperating with said sleeves, substantially as described.

6. In a drum, a one-piece shell having an integral central reinforcing band, a plurality of posts projecting outwardly through said shell and having fastening means cooperating with said band, sleeves carried by said posts and adjustable with respect to said shell, and tightening screws cooperating with said sleeves, substantially as described.

7. In a drum, a cylindrical shell of cast metal having relatively thin side walls with integral bands of relatively greater thickness extending thereabout at the edges thereof, substantially as described.

In testimony whereof I have hereunto set my hand.

GEORGE H. LOGAN.
